EZECHIEL WEINTRAUB, OF SCHENECTADY, NEW YORK, ASSIGNOR TO GENERAL ELECTRIC COMPANY, A CORPORATION OF NEW YORK.

MEANS FOR TRANSFORMING ELECTRICAL ENERGY.

1,086,101.

Specification of Letters Patent.

Patented Feb. 3, 1914.

Application filed February 28, 1902. Serial No. 95,660.

To all whom it may concern:

Be it known that I, EZECHIEL WEINTRAUB, a subject of the Czar of Russia, residing at Schenectady, county of Schenectady, State 5 of New York, have invented certain new and useful Improvements in Means for Transforming Electrical Energy, of which the following is a specification.

The invention hereinafter described and 10 claimed relates to certain improvements in vapor conductors and more especially to that type in which electrical energy is converted into light through the medium of vaporous or gaseous matter.

15 In lamps embodying my invention perhaps the most generally useful and convenient material is the vapor of mercury and it is of this vapor that I chiefly make use, though it is of course to be understood that 20 I do not wish my invention to be limited to the employment of this vapor only.

In lamps of the character described, various difficulties and disadvantages are attendant upon the means heretofore employed for starting the arc. The usual 25 method of starting, of which of course there are various modifications, is to impress upon the electrodes of the lamp, for a certain period or periods, a high electro-motive 30 force, many times greater in value than the normal electro-motive force at which the lamp is intended to operate. This starting electro-motive force operates or at least appears to operate to break down the high 35 initial resistance or opposition to current flow between the electrodes of the lamp whereupon the lamp starts.

My present invention, among other valuable features, provides a means whereby a 40 lamp of the type mentioned may be started into operation by the utilization of moderate electro-motive forces, such for example as those normally employed by the lamp, though my invention permits a wide range 45 of starting electro-motive force.

Before passing on to the explanation of my invention in detail it may perhaps be well to state first certain considerations 50 which may aid in explaining the theory of operation of the lamp. In general, I start the arc by projecting into its path the vapor of mercury or other similar vapor. It is not sufficient that this vapor should be of that form which would be produced by the 55 evaporation of mercury by heat, for when in

this condition it has been found that the mercury vapor is practically, or at least nearly, a non-conductor for the electric current so that the presence of such vapor not only does not help the lamp to start, but 60 actually hinders it. Something more is necessary and this necessity requires that the mercury should not only be in the form of a vapor, but this vapor should be in an ionized condition. It is perhaps impossible 65 to state exactly what this condition is but it will be sufficient for the present purpose to state that when in the ionized condition the mercury vapor is a good conductor of the electric current, whereas ordinary mercury vapor is practically a non-conductor. I have found that such ionized mercury vapor may be produced within the inclosing or containing member of the lamp by means of a supplemental or auxiliary 70 mechanism operating at comparatively low electro-motive force and that this ionized vapor once produced immediately causes current to pass between the main electrodes of the lamp, which thereupon operates normally. The lighting up of the main tube 75 of the lamp, so far as the eye can see, is or may be simultaneous with the initiatory production of the ionized vapor by the supplemental or auxiliary device. 80

After the lamp has been started, the supplemental or auxiliary mechanism or means for generating the ionized vapor may be cut out of circuit or otherwise put out of action if desired, and this operation may be performed either manually or automatically. I have found however that if this auxiliary or supplemental source of ionized vapor be continued in operation a most important advantage may be secured. When the lamp 90 is maintained in circuit under certain conditions either of impressed voltage or of current supply, it may become unstable in action. This may happen for example when the lamp is made to run with reduced current, in which case it may frequently flicker or go out entirely. If, however, the auxiliary or supplemental source of ionized vapor be maintained in action, this instability 95 disappears and the lamp will be steady and 100 stable in operation throughout extremely wide variation in impressed voltage or current supply. I account for this on the theory that any tendency of the lamp to go out, or any tendency to undue reduction 105

of current, is instantly counteracted by the supply of ions produced by the supplemental source, these ions immediately bringing back the flow of current to its normal 5 value.

My invention further comprises various features for assisting the beneficial effects of the starting means, particularly useful in relatively long lamps. In carrying out this 10 last feature of my invention I provide one of the electrodes of the lamp with a conducting medium extending in the direction of the other electrode. This conducting medium may be in the form of a carbon 15 filament, though in this connection I may employ a filament, rod, or other suitably shaped conductor of carborundum or of graphite or of mixtures of carborundum, graphite and clay since these materials 20 possess the valuable advantage that they do not occlude gases to any extent nor do they, by the action of heat, become chemically changed in such a manner as to produce 25 gases. This advantage is extremely important since, in lamps to which my invention 30 is to be applied, it seems to be necessary that the vacuum or degree of exhaustion should be as near absolute perfection as possible. Thus I get good results in long tubes with a vacuum represented by 1/1000 of a millimeter of mercury.

My invention comprises also other valuable features together with various details of construction and arrangement, all of 35 which will be set forth more specifically in the following description, taken in connection with the accompanying drawings, in which—

Figure 1 represents one embodiment of 40 my invention, and Fig. 2 an arrangement containing certain additional features.

In Fig. 1 a lamp is shown, the main body portion of which consists of a straight tube 1 of somewhat indefinite length as indicated 45 conventionally by the dotted lines 2, 2. The length of the tube varies in accordance with the voltage in connection with which the tube is to be used. The lower end of the lamp contains a body of mercury 3 extending 50 down into a contracted neck 4 of the tube, with the lower end of which communicates a terminal 5 which may be of platinum or other suitable material having the proper coefficient of expansion. The body of 55 mercury 3 above referred to, constitutes one of the operative electrodes of the lamp and is connected with the negative conductor leading from a source of direct current, whereby it acts as a cathode. At the opposite 60 end of the tube is the anode 6. This may be formed of various materials such as iron, silicon, carborundum, or mixtures of carborundum, graphite and clay, carbon, graphite or a mixture of graphite and clay. 65 Graphite, carborundum and clay possess the

advantage that they do not tenaciously retain occluded gases nor do they, when acted upon by heat, undergo such chemical change as would give rise to the production of gases, the advantage of which is set forth 70 above. The electrode 6, to which reference has been made, is connected by a platinum or other suitable wire 7 passing through a glass wall into an exhausted chamber 8 through which by means of a coiled or extensible wire 9, connection is made with the exterior terminal 10 of the lamp which terminal is connected to the other pole of the source of direct current. The object 75 of the supplemental exhausted chamber 8 is 80 to relieve the pressure around the joint between the platinum wire 7 and the glass surrounding it, thereby reducing, as far as possible, any tendency toward leakage of air into the main tube. In connection with the 85 main lamp electrodes thus described, there will be noticed an additional or supplemental electrode, consisting in this instance of a body of mercury 11, normally separated from the mercury 3 but in proximity 90 thereto, and contained within a cavity 12 from which depends a tubular extension 13 into which projects one end of a supplementary exterior terminal 14 sealed through 95 the glass forming the walls of the extension. 95

I find it extremely desirable, if not absolutely necessary, that the mercury should be introduced into the tube in as pure a condition as possible, and I find that this may be done by placing the mercury first within a 100 vessel, not shown, communicating with the main tube 1 through a suitable passage as, for example, through the tubular extension 24, and then distilling the mercury into the main tube in vacuum. The extension may 105 then be sealed off as shown. After the mercury has been introduced into the tube, the latter must be evacuated to as high a degree as possible, which is done by pumping, through the extension 15, and this pumping 110 must be continued for a greater or less length of time after the lamp has been put into operation in order to withdraw all occluded or other gases which may be set free in the tube during the initial operation of 115 the lamp. When gases are no longer given off, and the vacuum shows no signs of impairment, the connection between the tube and the pump may be sealed off.

In order to start the lamp on an ordinary 120 direct current circuit, the main terminals 5, 10, are connected with a source of current in such a manner that the mercury electrode 3 shall be the cathode and the electrode 6 the anode. The supplemental 125 electrode 14 is also connected to this source of current so as to form a supplemental anode. Resistances 16 and 17 may be connected respectively in series with the main and supplemental anodes to adjust the cur- 130

rent flow. These resistances also have a steadyng effect. The terminals of the lamp having been connected as described, the lamp may be started into operation by 5 gently shaking the lower end of the lamp, which may be supported from its upper end by the ring 18 or some other suitable arrangement. This act of shaking, which in some instances may amount to no more than 10 a delicate touching of the lamp, causes mercury to flow so as momentarily to connect the two electrodes 3 and 11, and upon their disconnection, as the mercury recedes, gives rise to an arc or discharge between the two 15 bodies of mercury. The accompanying liberation of ions by the electrical vaporization of the mercury instantly causes current to flow between the main electrodes 3 and 6 of the lamp, which is thereupon filled with 20 a brilliant whitish light. My present belief is that the action is a projection of ions from the cathode toward or to the anode, which forms a conducting path and ultimately an arc, thus enabling the normal 25 voltage of the lamp to initiate the flow of current between the main electrodes when such voltage unassisted would be incapable of doing so. It is certain that the initial 30 opposition to the flow of the main current in the tube, if such a word as opposition may be used, is very considerable and has heretofore required the application of an 35 electro-motive force of many hundreds of volts to the main electrodes of the tube in order so far to break down this initial opposition as to allow a moderate service electro-motive force of the order, say, of 100 volts, to set up and maintain the normal flow of 40 current in the tube. Electrically vaporizing mercury within the tube (vaporization merely by heating would be ineffective because the vapor thus produced in non-conducting), or otherwise liberating free ions at the surface, gives rise to a conducting 45 vapor which may be distinguished from the ordinary vapor of mercury by designating it as ionized vapor. This ionized vapor, being produced locally, spreads out through 50 the tube, as I believe by a propulsion of its charged molecules along the static lines of 55 force in the tube. The ions thus liberated by the vaporization of mercury at the surface of the main cathode 3 are therefore conveyed toward the main anode 6 and the whole tube flashes into brilliance, the migration of ions from the main cathode usually 60 reaching its normal rate instantaneously after the action has once been started up through the operation of the supplemental or auxiliary anode in the manner described.

It will be seen that while prior inventors have concentrated their efforts on devising means for conveniently generating electro-motive forces high enough to forcibly break down from without the initial opposition of

the tube, my invention, in the aspect I am now discussing, regardless of theory or nomenclature, is characterized by the fundamental distinction that I first weaken and, as it were, undermine this opposition to the flow of current so that I am then able to overcome it by service electro-motive forces if desired. The simplest way of practising my invention in its broadest aspect is to impress upon the main electrodes of a tube 70 in which the auxiliary electrode is either absent or inoperative a moderate electro-motive force, and then to shake the tube so as more or less violently to agitate or break up the surface of the mercury terminal, 75 whereupon the opposition to flow of current will be so far reduced as to enable the electro-motive force impressed upon the terminals to start the lamp into operation. 80

In order to assist the flow of current between the main electrodes of a lamp of the character described, I have discovered that it is very advantageous to bring one of the electrodes, as for example the anode, within electrical proximity so to speak of the other electrode, and this may be done by extending from the anode a suitable electrical conductor such for example as a carbon filament or rod or a filament or rod formed of graphite or carborundum or of mixtures of these substances and clay, this rod having one end electrically connected to the anode and the other end extending toward the cathode but not into contact therewith. This rod it may be found necessary 90 in many instances to support in a central position by means of a suitable anchoring device or devices. Such a structure I have represented in Fig. 2 in a lamp shown without its electrical connections. This lamp is 95 similar in most respects to that shown in Fig. 1 but contains in addition the anode extension 19 in the form of a small filament of material such as described. This filament is anchored by means of a ring or hook 100 20 supported by a hollow piece of glass 21 sealed through the wall of the main tube. This hollow glass body has a small opening 22 between the interior thereof and the tube, whereby when the main tube is exhausted the interior of the body may likewise be exhausted, thereby doing away with any danger to the vacuum of the tube should any accident such as cracking or the like occur to the glass body supporting the 105 anchoring ring or hook 20. 110

When the auxiliary arcing or starting device is put into operation, the conducting vapor proceeding from the main cathode 23 of the lamp seems, by the presence of the filament or rod 19, to be able more readily to reach the main anode than when no such rod or filament is used, the action being one in which the vapor, by reaching the projecting ends of the filament, flows along the 115 120 125 130

same, due to its conducting or some other quality until it reaches the anode. This extension of one of the lamp electrodes toward the other by an electric conducting medium is 5 particularly useful in connection with relatively long tubes.

I have set forth above that the auxiliary arc may be started by a manual agitation of the lower end of the tube which may, if desired, 10 be provided with a knob 24 to serve as a hold for the fingers. Instead, however, of manual operation, I may employ electrical or electro-mechanical means, and such means I have disclosed and claimed in applications 15 filed concurrently herewith.

The supplemental or auxiliary anode, by the coöperation of which with the main cathode the secondary or starting arc is produced, may if desired be cut out of circuit 20 after the lamp starts into operation, and for this purpose suitable automatic devices may be used, such as I have disclosed and claimed in other applications filed concurrently herewith. If, however, the supplementary or 25 secondary arc be maintained during normal operation of the tube, I find that there results the important advantage that in case the lamp for any reason has any tendency toward unstable operation, this is entirely 30 prevented. Furthermore where the main arc alone would be stable within a very narrow range of current, the range of stability is materially increased by the presence of the secondary arc, making it possible to vary 35 the main current of the tube from a small minimum value up to the point where the current is so great as to destroy the tube. By the use of an adjustable series resistance, the lamp may, so to speak, be turned up or 40 down, or, in other words, its luminosity increased or diminished without departing from a condition of stable operation. Since the lamp consumes a substantially constant voltage at its terminals at all currents, and 45 since I have found by experiment that the ratio of the light to the energy consumed in the tube itself is within wide limits substantially independent of the current density, the efficiency of the lamp under these dif- 50 ferent conditions remains practically constant. Thus if the resistance in series with the lamp is doubled, the current is practically halved, the drop of potential across the resistance remaining practically the same as 55 before, and the efficiency of the lamp the same as before or substantially so.

What I claim as new and desire to secure by Letters Patent of the United States, is,

1. In an electric lamp, the combination of 60 a light transmitting envelop, of main electrodes, an auxiliary electrode, means for bringing said auxiliary electrode momentarily into electrical connection with one of the main electrodes.

2. An electric vapor lamp provided with

separate paths for the flow of current through the lamp, and means for momentarily connecting one of said paths across a source of electrical energy.

3. The combination with the inclosing envelop, of a vapor electric device, of a vaporizable electrode, and an electrode coöperating with the vaporizable electrode and formed of a mixture of graphite and clay. 70

4. The combination with an exhausted inclosing envelop, of an electrode therefor adapted to emit vapor, and a coöperating electrode including graphite in its composition. 75

5. In an electric lamp, the combination of a light transmitting envelop, electrodes 80 communicating with the interior of said envelop, one at least of which electrodes is of vaporizable material, and a conducting rod, filament or the like extending a part only of the distance between said electrodes. 85

6. In an electric lamp, the combination of an envelop, electrodes communicating with the interior of said envelop, one at least of which electrodes is of vaporizable material, and a conducting rod, filament or the like 90 extending from one electrode a part only of the distance between said electrodes.

7. The combination of a light transmitting envelop, electrodes therefor adapted to operate respectively as anode and cathode, 95 and a conducting rod, filament or the like joined to the anode and extending toward but not into contact with the cathode.

8. In an electric lamp, the combination of a light transmitting envelop, electrodes communicating with the interior of said envelop, one of which electrodes is of vaporizable material, and a graphitic conductor located between said terminals. 100

9. The combination of an exhausted envelop, electrodes therefor, and a graphitic conductor, located within said envelop and extending between but not electrically connecting said electrodes. 105

10. The combination of an exhausted envelop, electrodes therefor, one at least of which is of vaporizable material, and a rod, filament or the like connected to one electrode within the envelop, and means for anchoring or otherwise suitably securing the 110 free portion of said rod, filament, or the like. 115

11. The combination of an exhausted envelop, main electrodes therefor, and an auxiliary electrode adapted to be brought momentarily into contact with one of said main electrodes. 120

12. The combination of an exhausted envelop adapted to inclose a vaporous conducting medium, non-identical paths for the 125 flow of current through the envelop, and means for momentarily connecting one of said paths across a source of electrical energy.

13. The combination of an exhausted en- 130

velop, electrodes therefor, one at least of which is adapted to emit vapor, and a conducting rod, filament or the like, extending a part only of the distance between two of said electrodes.

14. The combination of an exhausted envelop, electrodes therefor adapted to operate respectively as anode and cathode, and a conducting rod, filament or the like, joined to the anode and extending toward but not into contact with the cathode.

15. The combination of an exhausted envelop, main electrodes therefor, and an auxiliary electrode adapted to be brought momentarily into electrical connection with one of the main electrodes.

16. The combination of an envelop, electrodes therefor, one at least of which is of vaporizable material, and a conducting rod, filament, or the like extending from one

electrode a part only of the distance between said electrodes.

17. The combination of a vapor-emitting electrode, a non-vaporizable electrode, and a refractory filamentary conductor extending 25 between said electrodes and supported by the non-vaporizable electrode.

18. The combination of an envelop containing an attenuated atmosphere, electrodes therefor, one at least of which is of 30 vaporizable material, and a conducting rod, filament, or the like extending between the electrodes but out of connection with at least one of the electrodes.

In witness whereof I have hereunto set 35 my hand this 24th day of February, 1902.

EZECHIEL WEINTRAUB.
